UNITED STATES PATENT OFFICE.

ANDREW A. KUCHER, OF CHESTER, PENNSYLVANIA, ASSIGNOR TO WESTINGHOUSE ELECTRIC & MANUFACTURING COMPANY, A CORPORATION OF PENNSYLVANIA.

REFRIGERATING MACHINE.

Application filed December 28, 1923. Serial No. 683,156.

My invention relates to refrigerating machines, particularly to small capacity machines of the compression type which are suitable for household use and it has for an object to provide apparatus of the character designated which shall be self-contained and of such physical proportions as to permit of ready installation within the ice compartment of the average household refrigerator box. It has for a further object to provide a capable and efficient machine of such simple construction as to permit of a considerable reduction in the manufacturing costs of apparatus of this type.

These and other objects, which will be made apparent throughout the further description of the invention, may be attained by the employment of the apparatus hereinafter described and illustrated in the accompanying drawing in which the single figure is a view in sectional elevation of one form of my refrigerating machine.

It has usually been found necessary to associate with refrigerating machines heretofore developed, a refrigerator box of such special design as to be adapted to cooperate with and form an integral part of the machine. Furthermore, apparatus of this type has usually employed a motor of such ample power as to be capable of maintaining, by only intermittent operation, the desired temperatures within the refrigerator box, which type of operation has necessitated the employment of control devices for automatically starting and stopping the motor. All of the above features cooperate to provide a machine, the manufacturing cost of which is considerable.

In my apparatus, I provide a refrigerating machine which is a single, self-contained unit and which does not require the association therewith of any special type of refrigerator box, the machine being so constructed as to permit of ready installation in the ice chambers of most household boxes. Furthermore, I employ a motor of only sufficient power to maintain, by continuous operation, the desired temperature within the refrigerator box. I have found the electrical power thus consumed, is no greater than with the intermittently operated type of apparatus, and, as no automatic control devices are required, a considerable economy in the manufacturing cost is effected. The above basic features, combined with numerous other novel details

of construction hereinafter described, cooperate to provide a refrigerating machine of extremely low manufacturing cost and capable of operating effectively and cheaply under the exacting requirements of household use, with little or no attention.

Referring to the drawing for a more detailed description of my invention, I show an evaporating chamber 10 having vertical heat-absorbing walls 11 and a horizontal heat-absorbing wall 12. The evaporator 10 is preferably of annular conformation and has inner walls 13 and 14 within which is disposed a condensing chamber 15 having walls 16 and 17 spaced from the interior walls 13 and 14 of the evaporation chamber and the walls 16 and 17 of the condensing chamber, comprises an insulating or vacuum chamber 18 for retarding the conduction of heat from the condensing chamber to the evaporating chamber.

The lower ends of the evaporating chamber 10 and of the vacuum chamber 18 are both closed by a common sealing ring 19 which may be welded or secured thereto in any improved manner. Arranged in the upper portion of the condensing chamber 15 are a plurality of condensing coils 21 having an inlet connection 22 and an outlet connection (not shown), both of which are equipped with end fittings 23 adapted to receive a flexible hose or tube such as 24.

Disposed below the condensing coils 21 is a pressure-reducing valve 27. The inlet of the reducing valve 27 communicates with the condensing chamber 15 while the outlet is connected through a conduit 28 and a passage 29 with the evaporating chamber 10. A conduit 31 communicates with the passage 29 and extends into the lower portion of the evaporating chamber for the discharge of the liquid working fluid. The reducing valve 27 is actuated by a float 33 connected thereto by a lever 34.

Disposed within the condensing chamber 15 is a structural member 36 embodying a compressor housing 37, a motor housing 38, a receptacle 39 and a flange portion 41 which is secured to the sealing ring 19 by bolts 42 and forms a fluid-tight closure for the condensing chamber. Secured to the flange portion 41 are feet or skids 43 for supporting the machine. They are so constructed as not to interfere with the free circulation of air about the outer surfaces of the machine. Dis-

posed in the motor housing 38 is a driving motor 44 and secured to the structural member 36 by bolts 45 is a removable plate 46 for permitting ready inspection of the motor.

5 The motor 44 is provided with a vertically-disposed hollow shaft 47 supported at its lower end by a suitable bearing 48. The hollow shaft 47 rotatably engages at its upper end a compressor shaft 49 by means of a key

10 50. The key 50 is so constructed as to permit relative freedom of axial movement between the shafts. Rigidly secured to the compressor shaft 49 is a rotor 51 disposed within the compressor housing 37. An end plate 52 is

15 secured by bolts 53 to the housing 37 and forms a supporting bearing 54 for the upper end of the compressor shaft 49 and a retainer for the compressor rotor 51. The discharge port 55 of the compression mechanism is connected to a discharge conduit 56 having its upper end open and disposed in such manner as to cause the fluid discharged therefrom to impinge upon the upper wall 17 of the condensing chamber. A conduit 57 is

20 provided for conveying the liquid contained in the receptacle 39 to the bearing 54, which liquid serves as a lubricant. This lubricant, after passing downwardly through the working clearances provided in the compression mechanism is caught in an oil retainer 60 provided on the motor shaft 47 and fixedly secured thereto. Communicating means 61 is provided between the oil retainer 60 and the hollow portion of the motor shaft 47 for

25 draining the retainer free of the lubricant. My oil retainer 60 is so designed that the static pressure of the lubricant accumulating therein is sufficient to overcome the action of centrifugal force and the lubricant, therefore, drains inwardly towards the center of the shaft through the opening 61.

30 The lubricant passing downwardly through the hollow motor shaft 47 collects in a circular recess 62 provided in the removable plate 46, and lubricates the lower bearing 48.

35 An annular guard ring 63, which is fixedly secured to the removable plate 46 and slidably engages the motor shaft 47, is provided above the bearing 48 for preventing creepage of lubricant towards the motor. For removing lubricant from the lower portion of the motor chamber, a passage 64 is provided in the removable plate 46, which passage communicates with a conduit 65. The conduit 65 extends upwardly and terminates in the uppermost portion of the evaporating chamber.

40 Arranged concentrically without the upper portion of the conduit 65 and having its inlet end disposed below the end of the said conduit 65, is a suction conduit 66 for removing refrigerant vapor from the evaporator. The suction conduit 66 communicates with a suction passage 67 provided in the compressor housing 37 and this passage in turn communicates with the inlet port 68 of the compres-

sion mechanism. Provided in the suction conduit 66 is a restricted opening 69 which is disposed slightly below the level of the liquid working fluid in the evaporating chamber for the entrainment of a limited quantity of liquid working fluid in the vapor passing downwardly through the suction conduit 66. A conduit 70 extends from the lower portion of the vacuum chamber 18 to the vicinity of the inlet end of the suction conduit 66. Fluid-tight conductors 71 are provided in the removable plate 46 and are wired to the motor. They are adapted to be connected at their external ends to a source of electrical energy as by a cable 72.

70 The horizontal heat-absorbing surface 12 of the evaporator 10 is provided with a hollow insulated cover 75 forming an ice-making compartment 76 therewith. Ice molds, such as 77, may be placed within this compartment. The insulated cover 75 is provided with a handle 78 to facilitate removal of the ice. The upper horizontal heat-absorbing surface 12 of the evaporator is further provided with a plurality of radially-extending heat-conducting fins 81 which are rigidly secured thereto and which extend downwardly into the liquid working fluid. I have found from experiment that construction such as this materially aids in the rapid conduction of heat from the ice-making compartment. Should it be desired at any time to suspend the process of manufacturing ice, the cover 75 together with the molds 77 may be very easily removed and the heat-absorbing surface 12 directly exposed to the interior of the refrigerator box.

75 Having thus described one form of my invention the operation thereof is as follows: The evaporating chamber 10, the condensing chamber 15, and the receptacle 39 are filled to levels A, B and C, such as indicated on the drawing, with a suitable working fluid. The working fluid generally employed in my apparatus is a combination of a lubricant and a refrigerant which readily mix, one with the other, to form a homogeneous liquid or physical solution and which I have disclosed in my copending application serially numbered 617,884, filed February 8, 1923, and entitled Refrigerators. This working fluid is of such a character that its constituents are mechanically inseparable. Separation may, however, take place by the vaporization of one of the constituents due to sufficient temperature changes.

80 105 110 115 120 125 130 Upon electric current being conveyed through the cable 72 and the conductor 71 to the motor 44, the compression mechanism is actuated and discharges through the port 55 and conduit 56 a comingled liquid working fluid and vapor which is impinged upon the upper wall 17 of the condensing chamber. The liquid working fluid and the refrigerant vapor are thereby substantially separated

and the liquid falls into the receptacle 39, while the vapor passes outwardly to the condensing coils 21. The liquid working fluid within the receptacle 39, being subject 5 to the heat of the compression mechanism and partly to the heat of the motor, the refrigerant contained therein is vaporized off, leaving a body of liquid containing a high percentage of lubricant.

10 The warm refrigerant vapors passing radially outward come in contact with the coils 21 and are condensed by the cooling action thereof. The liquid refrigerant falls to the lower portion of the condensing chamber 15 and, upon sufficient rise of liquid level therein, the float 33 moves to open the pressure-reducing valve 27 to permit a flow of refrigerant liquid through the conduit 28, the passage 29, and the conduit 31 to the lower 20 portion of the evaporating chamber 10. Cold is then produced in normal manner by the vaporization of the liquid refrigerant. Heat is absorbed through the conducting walls 11 from the surrounding atmosphere and 25 through the conducting wall 12 from the ice-making compartment 76.

The refrigerant vapors generated in the evaporator rise to the upper portion thereof above the level of the liquid and are drawn 30 downwardly through the suction conduit 66 to the passage 67 and thence to the inlet 68 of the compression mechanism. A small amount of liquid working fluid continually flows through the restricted opening 69 and 35 is entrained in the refrigerant vapor passing downwardly through the suction conduit. This liquid working fluid aids in lubricating and sealing the compression mechanism in passing therethrough. The vacuum chamber 40 18 is continually exhausted by the compression mechanism through the conduit 70 which connects with the vapor-containing portion of the evaporating chamber. In this manner, conduction of heat through the walls 45 of the condensing chamber to the evaporating chamber is minimized.

Lubrication of the working parts of the apparatus is accomplished as follows: The liquid working fluid contained in the receptacle 39, which has been subjected to heat from the compressor and the motor, contains a high percentage of lubricant. It is conveyed by means of the conduit 57 and the difference in pressures prevailing between the condensing chamber 13 and the upper portion of the rotor 51 to the upper bearing 54. It flows 50 downwardly between the working clearances in this bearing to the transverse face of the rotor 51. A portion of the lubricant then 55 flows radially outward along its face and forms a very effective liquid seal, while the remaining portion flows downwardly through the working clearances provided in the mechanism and enters the bearing clearance 60 space provided between the compressor 65

shaft 49 and the compressor housing 37, because of gravity and the difference in pressures prevailing between the compressor and the rotor housings. As it flows downwardly, it is deposited upon the upper transverse face 70 of the motor shaft 47 and is thrown radially outward by the action of centrifugal force into the arrester 60. The static pressure of the lubricant accumulating in the arrester 60 is sufficient to overcome centrifugal force, 75 and the lubricant flows radially inward through the opening 61 into the hollow portion of the motor shaft 47.

The lubricant draining downwardly through the motor shaft 47 is deposited in 80 the circular recess 62 and immerses a portion of the bearing 48, thereby lubricating the same. It is removed from this bearing through the passage 64 and conduit 65 to the uppermost portion of the evaporating 85 chamber 10 and, because of the relatively lower pressure prevailing therein, flows out of the upper end of the conduit 65 and drains downwardly over the outer surface of this conduit and is entrained in the vapor passing 90 through the suction conduit 66. It is then conveyed in conjunction with the liquid coming through the restricted opening 69 to the inlet of the compression mechanism and serves to lubricate the working parts in passing therethrough. Upon the refrigerant vapor having entrained therein a quantity of the lubricant coming through the conduit 65 and a quantity of the liquid working fluid coming through the restricted opening 69 being 95 discharged from the conduit 56, the cycle of operation is completed. I prefer to operate my machine continuously to obtain the required refrigerating effect, as a low-powered motor may be employed and the necessity for expensive and intricate automatic starting and stopping appliances is eliminated. I have found the electrical power thus consumed is no greater than that consumed by the intermittently-operated type of 100 machine.

While I have shown my invention in but one form, it will be obvious to those skilled in the art that it is not so limited but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a refrigerating apparatus, the combination of a condenser, a compressor, motive means for the compressor, power-transmitting means interposed between the motive 115 means and the compressor, and an evaporation chamber arranged to house the condenser, the compressor, the motive means and the power-transmitting means.

2. In a refrigerating apparatus, the com-

120

125

130

bination of a condenser, a compressor, means for actuating the compressor, power-transmitting means connecting the compressor and the actuating means, and an evaporator, said 5 condenser, compressor, actuating means and power-transmitting means being encompassed by the evaporator.

3. In a refrigerating apparatus, the combination of an evaporator having a recess, 10 and a condenser, a compressor, a motor together with means for transmitting torque from the motor to the compressor arranged entirely within the recess of the evaporator.

4. A refrigerating apparatus embodying a 15 condenser, a compressor, motive means for the compressor, means for transmitting power from the motive means to the compressor, and an evaporator having heat absorbing walls, said first four elements being 20 rounded by the heat absorbing walls of the evaporator and said evaporator being adapted to be installed in the interior of a refrigerator box.

5. In a refrigerating apparatus, the combination of an evaporator, said evaporator having a recess provided therein, a closure 25 for the recess, a condenser, a compressor, means for driving the compressor, and power-transmitting means for connecting the 30 driving means and the compressor, said condenser, compressor, driving means and connecting means disposed within the recess of the evaporator.

6. In a refrigerating apparatus, the combination of an evaporating chamber, a condensing chamber disposed within the evaporating chamber, a rotary compressor, and a motor for driving the compressor, said compressor and said motor being disposed in adjacent end to end relation within the condensing chamber.

7. In a refrigerating apparatus in which a refrigerant fluid is successively vaporized, compressed and condensed in a repeating 45 cycle, an evaporating chamber having heat absorbing walls and a condensing chamber, a compressor, means for driving the compressor, and means for transmitting power from the driving means to the compressor 50 located inside the heat absorbing walls.

8. In a refrigerating apparatus, the combination of an evaporating chamber, of a condensing chamber containing refrigerant fluid disposed within the evaporating chamber, a compressor, and a motor for driving the compressor, said motor being disposed in heat conducting relation with the refrigerant fluid contained in the condensing chamber, whereby the heat of the motor is dissipated 60 through the intermediary of the refrigerating fluid.

9. In a refrigerating apparatus in which a working fluid composed of an intimate mixture of a refrigerant and a lubricant is employed, the combination of an evaporating 65

chamber, a compression mechanism and a condensing chamber disposed within the evaporating chamber, means for subjecting a quantity of the liquid working fluid to the heat of the compression mechanism for vaporizing off the refrigerant, and means for conveying the remaining liquid as a lubricant to the working parts of the apparatus. 70

10. In a refrigerating apparatus in which a refrigerant fluid is vaporized, compressed and condensed, the combination of an evaporator having a recess provided therein, a structural member for insertion within the recess of the evaporator, said structural member forming a motor housing and a receptacle 80 for lubricating fluid, and a compressor disposed in the receptacle.

11. In a refrigerating apparatus, the combination of a compressor, a motor, an evaporator provided with a recess and a structural member for insertion in the recess of the evaporator, said structural member forming a fluid tight housing for the motor and a housing for the compressor and defining 90 with the evaporator a condensing chamber. 90

12. In a refrigerating apparatus in which a refrigerant fluid is vaporized, compressed and condensed, the combination of an evaporator, a motor disposed within the evaporator, a fluid-tight housing for the motor, a compressor disposed within the evaporator, means for supplying a lubricating fluid to the motor housing for lubricating the motor, and means constituting a fluid-withdrawal path 95 extending between the interior of the motor 100 housing and the inlet of the compressor.

13. In a refrigerating apparatus in which a refrigerant fluid is vaporized, compressed and condensed, the combination of an evaporator, a motor disposed within the evaporator, a fluid-tight housing for the motor, a compressor connected to the motor, and communicating means between the inlet of the compressor and the motor housing, whereby 105 the suction pressure of the compressor is substantially maintained in the motor housing. 110

14. In a refrigerating apparatus in which a working fluid is vaporized, compressed and condensed, the combination of a condenser, a motor housing, a motor disposed therein, 115 means for supplying a lubricating fluid to the motor housing for lubricating the motor, a compressor driven by the motor, an evaporator for vaporizing liquid working fluid, and conduit means connecting first with the motor housing for withdrawing lubricating fluid therefrom, secondly with the evaporator for withdrawing vaporous working fluid therefrom and again with the evaporator for entraining in the evaporator liquid working fluid in the vaporous working fluid withdrawn therefrom. 125

15. In a refrigerating apparatus in which a refrigerant fluid is vaporized, compressed and condensed and in which a working fluid 130

- composed of an intimate mixture of a refrigerant and a lubricant is employed, the combination of an evaporator, a receptacle containing liquid working fluid disposed within the evaporator, a compressor immersed in the liquid working fluid contained in the receptacle, whereby the heat of the compressor is utilized to vaporize off the refrigerant contained in the liquid working fluid, and means 5 for conveying the liquid thus treated as lubricant to the working parts of the apparatus.
16. In a refrigerating apparatus in which a refrigerant fluid is vaporized, compressed and condensed and in which a working fluid composed of an intimate mixture of a refrigerant and a lubricant is employed, the combination of an evaporator, a receptacle containing liquid working fluid disposed within the evaporator, a compressor immersed in the liquid working fluid contained in the receptacle, whereby the heat of the compressor is utilized to vaporize off the refrigerant contained in the liquid working fluid, a motor for driving the compressor, and means for 10 conveying the liquid which has been subjected to the heat of the compressor as lubricant to the working parts of the compressor and thence to the working parts of the motor.
17. In a refrigerating apparatus in which a refrigerant fluid is vaporized, compressed and condensed and in which a working fluid composed of an intimate mixture of a refrigerant and a lubricant is employed, the combination of an evaporator, a receptacle containing liquid working fluid disposed within the evaporator, a compressor immersed in the liquid working fluid contained in the receptacle, whereby the heat of the compressor is utilized to vaporize off the refrigerant contained in the liquid working fluid, a motor for driving the compressor, means for conveying the liquid which has been subjected to the heat of the compressor and the motor as lubricant to the working parts of the compressor and the motor, and means for conveying the lubricant discharged from the compressor and the motor to the inlet of the compressor.
18. In a refrigerating apparatus, the combination of an evaporating chamber, a condensing chamber disposed within the evaporating chamber, a compressor, a motor for driving the compressor and power-transmitting means connecting the motor and the compressor, said compressor, motor and connecting means being entirely disposed within the condensing chamber.
19. In a refrigerating apparatus, the combination of an evaporating chamber, a condensing chamber disposed within the evaporating chamber, insulating means interposed between the two chambers, a compressor, means for driving the compressor, and power-transmitting means connecting the driving means and the compressor, said compressor, said driving means and said connecting means being disposed within the condensing chamber.
20. In a refrigerating apparatus, the combination of a motor, a compressor, an evaporator element, a casing forming a condensing chamber, said casing having an opening provided therein and said casing extending within the evaporator element, and a structural member for housing the motor and the compressor and extending through the opening in the casing into the condensing chamber, said structural member forming a closure for the opening in the casing of the condensing chamber.
21. In a refrigerating apparatus, the combination of an evaporator, a condensing chamber disposed within the evaporator, a motor and a compressor disposed within the condensing chamber and means provided within the condensing chamber for maintaining a predetermined level of liquid working fluid therein.
22. In a refrigerating apparatus, the combination of an evaporator, a condensing chamber disposed within the evaporator, a motor and a compressor disposed within the condensing chamber, means for conveying liquid working fluid from the condensing chamber to the evaporator, a valve for controlling the flow of the working fluid, and a float provided within the condensing chamber for actuating the valve.
23. In a refrigerating apparatus in which a refrigerant fluid is continuously circulated in a closed cycle, the combination of a plurality of ice molds, an evaporator for containing a supply of cooling liquid and having a heat-absorbing surface disposed in heat-exchanging relation with the ice molds, and structural heat-conducting means provided upon the said heat-absorbing surface of the evaporator and extending inwardly within the evaporator to the supply of cooling liquid contained therein.
24. In a refrigerating apparatus, the combination of an evaporator, a condensing chamber arranged within the evaporator, a motor and a compressor together with power-transmitting means for connecting the motor and the compressor disposed within the condensing chamber, and an ice-making compartment superimposed upon the evaporator.
25. In a refrigerating apparatus, the combination of a compression mechanism, an evaporating chamber, a condensing chamber, an insulating chamber interposed between the evaporating and the condensing chambers, and means associated with the compression mechanism for partially evacuating the insulating chamber.
26. In a refrigerating apparatus, the combination of an evaporating chamber, a condensing chamber disposed within the evapo-

rating chamber and maintained in spaced relation thereto, and means for partially evacuating the space intervening between the evaporating and condensing chambers, 5 whereby conduction of heat therebetween is retarded.

27. In a refrigerating apparatus, the combination of an evaporating chamber, a condensing chamber disposed within the evaporating chamber, an insulating chamber interposed between the evaporating chamber and the condensing chamber, a compression mechanism disposed within the condensing chamber, and communicating means provided between the insulating chamber and the inlet of the compression mechanism.

28. In a refrigerating apparatus, the combination of an evaporating chamber, a condensing chamber disposed within the evaporating chamber, a motor and a compressor disposed within the condensing chamber, an insulating chamber interposed between the evaporating and condensing chambers for retarding conduction of heat therebetween, 25 and means constituting a fluid-withdrawal path for connecting the insulating chamber to the inlet of the compressor, whereby a pressure substantially equal to that of the suction pressure of the compressor is continuously maintained in the insulating chamber during operation of the apparatus.

29. In a refrigerating apparatus, the combination of a condenser, an evaporator, and a hermetically sealed motor-compressor unit

arranged at least partly within the confines 35 of the evaporator.

30. In a refrigerating apparatus, the combination of condensing means, a hermetically sealed motor-compressor unit, and an evaporator arranged exteriorly of and 40 around said motor-compressor unit.

31. In a refrigerating apparatus, the combination of condensing means, a hermetically sealed motor-compressor unit, and an evaporating chamber arranged to house at 45 least a portion of said motor-compressor unit.

32. In a refrigerating apparatus, the combination of condensing means, an evaporator, a compressor, a motor, and power-transmitting means for connecting the motor to the compressor, said evaporator being arranged to house the compressor, the motor and the power-transmitting means for connecting the motor to the compressor. 55

33. In a refrigerating apparatus, the combination of condensing means, a compressor, a motor, power-transmitting means connecting the motor to the compressor, and an evaporator located exteriorly of and extending 60 around the compressor, the motor and the power-transmitting means for connecting the motor to the compressor.

In testimony whereof, I have hereunto subscribed my name this 13th day of December, 1923.

ANDREW A. KUCHER.
